Patented Feb. 13, 1917.

FIG. 1.

FIG. 2.

FIG. 3.

Inventor
William D. Moore,

Jas. L. Shadmore

his Attorney.

UNITED STATES PATENT OFFICE.

WILLIAM D. MOORE, OF CRESTON, IOWA.

MOLD FOR CASTING POURED-CONCRETE BLOCKS.

1,215,961.

Specification of Letters Patent.

Patented Feb. 13, 1917.

Application filed July 27, 1916. Serial No. 111,678.

To all whom it may concern:

Be it known that I, WILLIAM D. MOORE, a citizen of the United States, residing at Creston, in the county of Union and State 5 of Iowa, have invented certain new and useful Improvements in Molds for Casting Poured-Concrete Blocks, of which the following is a specification.

This invention relates to a mold for casting 10 poured concrete blocks or bricks on end, and is especially designed to provide a mold consisting of sections or members which can be readily and quickly assembled into a series or plurality of molding spaces, and removably secured together by any suitable or 15 convenient means.

The main object of the invention is to construct a simple, inexpensive, durable and 20 thoroughly efficient device in the method of making poured concrete blocks or bricks on end.

Another object of the invention is to provide molds constructed entirely from suitable sheets of metal which can be rapidly assembled, and so constructed that the entire mold can be removed before the block or 25 brick is strong enough to handle, said molds requiring but little floor space and no bottom other than a suitable platform.

A further object of the invention is to provide molds for poured concrete bricks or blocks in sections, which may be connected together in series, and in which the partitions separating the sections are removably 30 connected to the side members of each section and so constructed that a handle is formed by an integral extension at each side or end thereof, said partition plates always 35 resting flush and level with the upper edge 40 of each mold.

A still further object of the invention is to provide in connection with my improved mold an attachment forming a partition which is employed to apply a facing of different or richer material than that constituting the body of the block, said attachment projecting above the mold and forming a handle by which it may be readily removed from the mold.

The foregoing and such other objects as 50 may appear from the ensuing description are attained by the novel features of construction, arrangement and location of the parts, hereinafter more fully described, illustrated in the accompanying drawings, and particularly pointed out in the claims ap-

pended hereto, it being understood that slight changes in the form, proportions, and minor details of the construction may be resorted to without departing from the spirit 60 or sacrificing any of the advantages of the invention.

In the accompanying drawings it will be seen that:

Figure 1, is a plan view of the improved 65 device embodying my invention.

Fig. 2, is a side elevation of the same, and

Fig. 3, is a perspective view showing the members of each mold before the parts are assembled or joined together.

70

Similar numerals of reference are employed to designate corresponding parts throughout the several figures of the drawings.

In the embodiment of this invention as 75 illustrated and which shows a preferred construction, the numerals 1 designate the side members of each mold box, said side members being preferably formed of flexible sheet steel and provided with the inwardly 80 projecting portions 2 at the central portion thereof and an outwardly projecting longitudinal flange 3 at each side.

The partition plates for separating one 85 mold from the other consist each of a flat metal plate 4 having integral extensions bent oppositely at right angles to the plate at its top and bottom portion at each side thereof, said extensions on each side of each plate being arranged one above the other and 90 projecting in opposite directions in vertical alinement, the top and bottom right angle extensions 5 at the right hand side of the plate projecting in opposite directions, and the intermediate right angle extensions 6 being positioned in a direction opposite to the 95 extensions 5, while the corresponding extensions on the left hand, or opposite side of the plate project in a direction opposite to those on the right hand side, whereby in assembling each mold a top and intermediate extension 5 and 6, and a bottom and intermediate extension 5 and 6 will contact with the outer edge or surface of the flange 3 of 100 each side member and hold said member in its proper position and alinement, and each side of each of said plates 4 is provided with a lateral extension 7 which projects beyond the mold proper, thereby forming a 105 handle for manipulating the plates and readily removing them from the molds, as clearly shown in the drawings.

100

105

110

When it is desired to apply a facing of different or richer material than that from which the body of the block is formed, I employ a flat metal plate 8, provided at 5 each side thereof with an integral flange 9, at right angle to the body of the plate, the outer or terminal edge of each flange resting in contact with the inwardly inclined wall of each side member 1, thereby 10 forming a suitable space between the plate 8, and partition plate 4, to receive the facing material. Each of the plates 8 are made longer than the mold members so that it projects above the top of the molds thereby 15 forming an extension 10, constituting a handle therefor, by which the said plate 8 may be manipulated in placing it within and removing it from the mold.

It will be understood that the concrete 20 for the body of the block and also the facing material is so mixed that it will pour freely, hence when the plate 8 is withdrawn, which is immediately after the material for forming the body of the block and the facing 25 is poured, the material then being in a plastic condition permits the body and facing to readily unite and adhere together thus forming a solid and integral block.

From the foregoing, it will be readily ob- 30 vious that the molds require no bottom other than a suitable platform, and that the mold is so constructed that it can be rapidly assembled and the entire mold can be quickly removed before the block is strong 35 enough to handle.

It will also be obvious that any suitable means may be utilized for clamping or holding a series of the molds together, and while I have shown a series of four molds any 40 suitable number of the molds may be connected together, the partition plates 4 separating one mold from the other.

Having thus described my invention what I claim and desire to secure by Letters Patent is:

1. A mold for concrete blocks comprising two detached side members, each of said side members having an inwardly projecting central portion extending throughout 45 its height and an outwardly integral right

angle projecting flange at each end thereof, and a plate at each end of the mold provided with an integral right angle oppositely disposed extension at the top and bottom of each side, and an intermediate oppositely disposed right angle extension at the top and bottom portion at each side thereof, whereby a top and intermediate extension and a bottom and intermediate extension will contact with the outer edge of the projecting flange of each of the side members. 55

2. A mold for concrete blocks comprising two detached side members, each of said side members having an inwardly projecting central portion extending throughout 60 its height and an outwardly integral right angle projecting flange at each end thereof, a detached partition plate at each end having an integral right angle oppositely disposed extension at the top and bottom of 65 each side; an intermediate oppositely positioned right angle extension at the top and bottom portion at each side thereof, said top and intermediate extensions being positioned opposite each other in vertical alinement and adapted to contact with the outer edge of the outwardly projecting flange of each of the side members, and said partition plate having a lateral extension formed on each side between and projecting beyond the 70 said right angle extension to form a handle. 75

3. A mold for concrete blocks comprising two detached side members, each side member having an outwardly projecting flange at each end thereof, and an inwardly projecting central portion extending throughout its height, a partition plate provided with top and bottom and intermediate right angle oppositely disposed integral extensions at each side thereof adapted to contact 80 with the outer edge of the projecting flange of each side member, in combination with a plate having right angle integral flanges at each side thereof adapted to contact with the inner face of the inclined walls of each 85 of the side members, and having an extension projecting beyond the top of the mold to form a handle therefor. 90 95

WILLIAM D. MOORE.
